G. B. WARNER

COMBINED RADIATOR CAP AND FILLING TUBE

Filed Oct. 24, 1927

Inventor
George B. Warner
By his Attorney
George C. Henrique

UNITED STATES PATENT OFFICE.

GEORGE B. WARNER, OF NEW YORK, N. Y.

DESIGN FOR A COMBINED RADIATOR CAP AND FILLING TUBE.

Application filed October 24, 1927. Serial No. 23,866. Term of patent 3½ years.

To all whom it may concern:

Be it known that I, GEORGE B. WARNER, a citizen of the United States, residing at New York, in the county of New York and State of New York, have invented a new, original, and ornamental Design for a Combined Radiator Cap and Filling Tube, of which the following is a specification, reference being had to the accompanying drawing, forming part thereof.

In the accompanying drawings:

Figure 1 is a side elevation of a combined radiator cap and filling tube showing my new design, and

Figure 2 is a front elevation thereof.

I claim:

The ornamental design for a combined radiator cap and filling tube as shown.

G. B. WARNER.
